DESIGN FOR A GLOVE

Sylvan M. Straus, Gloversville, N. Y.

Application August 26, 1937, Serial No. 71,332

Term of patent 3½ years

To all whom it may concern:

Be it known that I, Sylvan M. Straus, a citizen of the United States of America, residing in Gloversville, in the county of Fulton and State of New York, have invented a new, original, and ornamental Design for a Glove, of which the following is a specification, reference being had to the accompanying drawing, forming part thereof, wherein,

The design is characterized by a row of adjoining diamond shaped units placed adjacent the gauntlet edge and on the center portion of the back of the glove, as shown.

I claim:

The ornamental design for a glove, substantially as shown, and described.

SYLVAN M. STRAUS.
